UNITED STATES PATENT OFFICE.

PHILLIP A. UDALL, OF STOCKTON, CALIFORNIA.

VALVE-GRINDING MACHINE.

1,295,940.

Specification of Letters Patent.

Patented Mar. 4, 1919.

Application filed October 9, 1917. Serial No. 195,647.

To all whom it may concern:

Be it known that I, PHILLIP A. UDALL, a citizen of the United States, residing at Stockton, in the county of San Joaquin,

5 State of California, have invented certain new and useful Improvements in Valve-Grinding Machines; and I do declare the following to be a full, clear, and exact description of the same, reference being had 10 to the accompanying drawings, and to the characters of reference marked thereon, which form a part of this application.

This invention relates to an improved means for grinding valves of internal combustion engines. The object of the invention is to provide a machine capable of grinding a plurality of valves at one time in the best improved manner but much more efficiently and quickly than is now the 20 common practice. To this end I provide a mechanical movement whereby the grinding rods are imparted an intermittent reversing motion so that the valves will be turned approximately two-thirds of a revolution in one direction, and then reversed one-third of a revolution and so on, which is the proper method of grinding them so as to prevent the cutting in of grooves by the grit. I also provide a means for intermittently lifting 25 the valves as they are being ground, so as to allow the grit to flow in between the seats and the valves.

A still further object of the invention is to provide a suitable lever mechanism for 30 lifting the grinding rods in order to position the valves in the machine, and I also provide a compensating means to maintain the proper relative length of the rods between the driving gears and the valves.

40 A further object of the invention is to produce a simple and inexpensive device and yet one which will be exceedingly effective for the purposes for which it is designed.

45 These objects I accomplish by means of such structure and relative arrangement of parts as will fully appear by a perusal of the following specification and claims.

In the drawings similar characters of 50 reference indicate corresponding parts in the several views.

Figure 1 is an assembly view of my complete mechanism, showing but one grinding

rod and connected parts. In practice, however, a large number of grinding rods may 55 be positioned at one bench and operated by the same mechanism.

Fig. 2 is a plan view of my improved gearing for imparting the intermittent reversing movement to the grinding rods. 60

Fig. 3 is a side elevation of the structure shown in Fig. 2.

Fig. 4 is a fragmentary view showing how the main driving shaft is geared to the grinding rods. 65

Fig. 5 is a detached view of the cam used for operating the valve lifters.

Referring now more particularly to the characters of reference on the drawings, the numeral 1 designates the bench on which 70 may be set the cylinder heads 2, or other valve seating members found desirable, arranged to receive the valves 3. For each of the valves 3 I provide a grinding rod 4, which at its lower end is provided with a 75 slideable spring pressed chuck 5 carrying the driver 6, which driver 6 fits into the slot or holes of the valve head 3. The upper end of the rod 4 is slideable through a bushing or sleeve 7, and at its upper end is provided with a beveled gear 8. This beveled gear 8 meshes with another beveled gear 9 on a small shaft 10. Such shaft 10 is in turn provided with another beveled gear 11 at its opposite end which meshes with still 80 another beveled gear 12 on the main driving shaft 13. 85

As previously noted, this shaft 13 can be arranged to operate as many of the grinding rods 4 as it may be desired to set over a 90 single bench or table. Each rod 4 is provided with a pair of spaced collars 14, between which projects a yoke 15 of a hand lever 16. When the rod 4 is to be placed in driving relation with the valve 3 (during 95 which period it is of course desirable to place it out of driving relation with the shaft 13) the lever 16 is used to lift the rod 4. The rod 4 slides in the bushing 7 and lifts the gear 8 out of driving relation with the gear 9, which, of course, stops the movement of the rod and permits the valve 3 to be placed in or removed out of driving relation with such rod 4. 100

To each grinding rod 4 is imparted a 105 revolution in one direction with an inter-

mittent partial revolution in the reverse direction, by means of the following structure, namely: A gear 17 is fixed to the shaft 13 and intermeshes with a large gear 18 turnable on a stub shaft 19. This gear 18 in turn meshes with a gear 20 fixed to a shaft 21. This shaft 21 is journaled on an oscillating arm or pendulum 22, mounted for oscillation upon the shaft 19. On the opposite end of the shaft 21 is a large gear 23 which meshes with a smaller gear 24 fixed off-center on a driving wheel 25 keyed to a driving shaft 26. A link arm 27 is sleeved at one end on to the shaft 21, and at the other end on the stub shaft 28 of the gear 24. The function of this link is to maintain the gears 23 and 24 in mesh during the oscillating movement of the pendulum 22. The operation of these gears is as follows:

Assuming that the gear 24 is in a position indicated by the letter "A," and that the driving wheel 25 is moving in the direction indicated by the arrow in Fig. 3, this gear 24 can not drive the big gear 23 fast enough for the throw of the arm 27 and so it moves the pendulum 22 and shaft 21 to the right, and at the same time rotates the gear 23 in the direction shown by the arrow on its arm (see Fig. 3). This turns the shaft 21 and the gear 20 in the same direction and drives the gear 18 in the opposite direction or in the direction shown by the arrow in Fig. 3. This movement through the medium of the gear 17 and the shaft 13, drives the grinding rod 4, for a portion of its revolution, in one direction. When the gear 24, however, reaches the point as at "B" and starts from that point back again on its revolution, it swings the pendulum in the opposite direction. The gears may be so proportioned that the movement on the right hand swing of the pendulum turns the gear 18 approximately two-thirds of a revolution. The relation of the gears is also such that on the swing of the pendulum to the left, no movement in the direction of the arrow is imparted to the gear 18, but on the contrary its movement is reversed by the swinging pull of the pendulum, which of course reverses the movement of the gear 17, driving shaft 13 and grinding rod 4 for approximately one-third of a revolution. Thus it will be seen that the valve 3 will be driven the greater part of a revolution in one direction, and its movement reversed for a small part of a revolution and so on which is the proper movement to impart to it to grind it efficiently.

On the main driving shaft 26, I provide a pulley 29 connected by a belt 30 with another pulley 31 on a shaft 32. On this shaft 32 are one or more cams 33, which operate against the corresponding rollers 34

mounted on levers 35. These levers 35 are connected by rods 36 connected through the medium of certain lever and link construction 37 (not particularly described herein) so arranged and relatively positioned that when the rod 36 is lifted, it lifts a bar 38 continuously in the same plane whereby set screws 39, carried by said bar, will engage and lift the valves 3 as is the approved practice during the grinding operation. 70 75

From the foregoing description it will be readily seen that I have produced such a device as substantially fulfills the object of the invention as set forth herein.

While this specification sets forth in detail the present and preferred construction of the device, still in practice, such deviations from such detail may be resorted to as do not form a departure from the spirit of the invention, as defined by the appended 80 85 claims.

Having thus described my invention, what I claim as new and useful and desire to secure by Letters Patent, is:

1. A valve grinding machine comprising 90 in combination with a plurality of grinding rods arranged for engagement with the valves, a means common to all the rods for rotating them in one direction and intermittently reversing such rotation for a fraction of a revolution, and means for intermittently lifting the valves during the latter operation, such means including an arm suspended lengthwise of the valve stem and under the same, set screws on the arm in alignment with each stem, a cam mounted in driving relation with the means for rotating the grinding rods, and a cam-actuated rod connected with the suspended arm whereby the arm and the valve stems thereabove will be raised at predetermined points in the rotation of the grinding rods. 95 100 105

2. A valve grinding machine comprising 110 in combination with a plurality of grinding rods arranged for engagement with the valves, a means common to all the rods for rotating them in one direction and intermittently reversing such rotation for a fraction of a revolution, such means including a driven gear connected in driving 115 relation with the grinding rods, a suspended pendulum having its point of oscillation concentric with the driven gear, a stub shaft carried in the lower end of the pendulum, a gear on the shaft meshing with the driven gear, an annular driving member, a gear fixed to the driving member off-center thereof, a gear on the pendulum shaft meshing with said fixed gear, and an arm sleeved onto the pendulum shaft and the fixed gear shaft to hold the last named gears in mesh during the rotation of the driving member.

3. A valve grinding machine comprising 130 in combination with a plurality of grinding

rods arranged for engagement with the valves, a driven gear on each rod, a single driven shaft connected in driving relation with all the gears on the grinding rods, and 5 means whereby each gear may be placed out of driving relation with the driving shaft independently of the others such

means including bushings, the rods being slideable through the bushing whereby they may be moved to lift the gears clear of the 10 connection with the driving shaft.

In testimony whereof I affix my signature.

PHILLIP A. UDALL.
